UNITED STATES PATENT OFFICE.

JOHN HAVRAN, OF PORTLAND, OREGON.

CURTAIN-SHADE CIRCUIT-CLOSER.

1,392,641.

Specification of Letters Patent.

Patented Oct. 4, 1921.

Application filed October 18, 1916. Serial No. 126,391.

To all whom it may concern:

Be it known that I, JOHN HAVRAN, a citizen of the United States, residing at Portland, in the county of Multnomah and State of Oregon, have invented certain new and useful Improvements in Curtain-Shade Circuit-Closers, of which the following is a specification.

This invention has relation to electric circuit closers conjunctively utilizable as shade roller brackets, and the nature and objects thereof will be readily apparent to those skilled in the art to which it appertains in the light of the following explanation of the accompanying drawings, illustrating what I now believe to be the preferred embodiment, or mechanical expression, of my invention, from among other forms and arrangements within the spirit 20 thereof, or the scope of the appended claims.

However, an object of the invention is to provide an electric circuit closer in the form of a supporting bracket for a shade roller, said bracket being disposed in circuit with an audible signal and a source of current whereby rotation of the shade roller due to the lowering or raising of the same by unauthorized persons results in the energization of the circuit and the consequent sounding 30 of the signal, giving notice to the occupants of the dwelling that such movement of the shade has taken place.

Another object of the invention is to provide a shade roller bracket having the above 35 named characteristics which is adapted to be secured to the side face of a window casing.

A still further object of my invention is to provide in combination with one form of circuit closer shade roller bracket, a closed 40 main circuit including therein said brackets and a relay or its equivalent, and a local circuit including an audible signal, whereby upon rotation of the shade roller due to movement of the shade, the main circuit 45 may be broken resulting in the consequent energization of the local circuit and the sounding of the signal.

A still further object of the invention is to provide another form of shade roller 50 bracket having the above named characteristics and an improved trunnion associated with said bracket and adapted for use in connection with the ordinary type of shade roller in place of the usually cylindrical trunnion, whereby upon rotation of the roller

due to movement of the shade, the contact may be created through the trunnion.

In addition to the foregoing, my invention comprehends improvements in the details of construction and arrangement of the 60 correlated parts to be hereinafter more fully described and particularly pointed out in the appended claims.

In the accompanying drawings in which similar and corresponding parts are designated by the same characters of reference throughout the several views in which they appear:

Figure 1, is a view in front elevation of a shade roller supported in brackets constructed after the manner of my invention, and illustrating one form of wiring and signal apparatus used in connection therewith.

Fig. 2, is a detail view of the ring on the shade for retaining the same in lowered position, and the manner of its use.

Fig. 3, is a detail view of a button used in connection with the ring of Fig. 2.

Fig. 4, is an end view of the bracket for supporting the cylindrical trunnion and 80 containing the contacts.

Fig. 5, is a section on line 5—5 of Fig. 4.

Fig. 6, is a view of one of the insulating plates.

Fig. 7, is a view of a form of contact 85 plate.

Fig. 8, is an end view of one of the brackets for supporting the angular trunnion of the shade roller.

Fig. 9, is a section on the line 9—9 of Fig. 8.

Fig. 10, is a view of one of the plates forming a part of the bracket shown in Fig. 8.

Fig. 11, is a view of a plate similar to 95 the plate shown in Fig. 10.

Fig. 12, is a side view of one end of the shade roller.

Fig. 13, is a diagrammatic view illustrating a pair of relays and associated wiring 100 and an audible signal, in connection with one form of circuit closer shade roller bracket, illustrating the operation of the closed circuit system.

Fig. 14, is a view in side elevation of one 105 of the end brackets for supporting the trunnion of a shade roller, and having means for preventing longitudinal movement of the shade roller thereby preventing the possibility of accidental electrical contact.

Fig. 15, is a view in side elevation of a further modified form of contact circuit closing shade roller bracket for use in connection with an open circuit system of wiring.

Fig. 16, is a view in side elevation of a still further modified form of bracket for use in connection with a closed circuit system of wiring, being of the type designed 10 to be secured to the side facings of the window frames.

Fig. 17, is a vertical section on the line 17—17 of Fig. 16.

Figs. 18 and 19 respectively, are views in 15 elevation of the insulating and metallic disks employed in connection with that form of bracket illustrated in Fig. 16.

Fig. 20, is a still further modified form 20 of shade roller supporting bracket designed for use in connection with a closed circuit system of wiring and of the type designed to be secured to the side facing of a window frame.

Figs. 21 and 22 respectively are views in 25 elevation of the insulating and metallic disks forming a part of the bracket shown in Fig. 20.

Fig. 23, is a view in front elevation of a bracket designed to be secured to the side 30 facing of a window frame for supporting the opposite end of the shade roller from that end associated with the circuit closing bracket and adapted to preclude longitudinal movement of the shade roller.

With reference to the drawings 1 indicates 35 a shade, supported upon a shade roller 2 having an angular, and a cylindrical trunnion designated 3 and 4 respectively. The angular trunnion 3 is supported in a bracket 40 which comprises an attaching portion 5, and an extension 6, conforming very closely to the form of such brackets at present in use, but provided with a series of circular plates 7 secured to the extension by means of 45 threaded or the like, fastenings 8, and having a central angular opening 9, adapted to receive the trunnion 3 of the shade roller. This trunnion may be engaged in the openings 9 of the plates by passing the trunnion 50 through a slot 10 radially provided in the disks or plates, and intersecting said openings. A plate 11 is disposed between adjacent pairs of the plates 7, and is provided with an angular opening 12, similar to the 55 opening 9, but slightly shorter in length, as the result of which an edge 13 is defined at the lower portion of the opening 9, for engaging a notch 14 in the angular trunnion 3. This edge is clearly shown in Fig. 8.

The cylindrical trunnion is supported in 60 a bracket having an attaching portion 15, and an extension 16 similar to brackets of this kind heretofore provided and having a central opening 17. A circular disk of insulation 18 is disposed in contact with the

extension 16, and is provided with an opening centered for registration with the opening 17. A disk 19 is next disposed in engagement with the disk of insulation and is provided with a central opening 20, for registration with the openings mentioned before, the opening 20 however having a horizontal flattened portion 21. A second disk of insulation 22 is disposed against the disk 19 and has a central opening similar to the 70 disk 18 and finally an outer disk 23 is provided which conforms in shape and size to the adjacent disk 22 and has a central opening. These disks are secured to the extension of the bracket 16 by means of threaded, or the like fastenings 24, extending through openings in said disks, the openings in the disk 19 being slightly enlarged to permit the insertion of insulating bushings 25 around the fastenings. 75

It will be observed, upon reference to Figs. 4 and 5 that the central opening 20 is wider than the central opening in the disk 23 and that the central circular openings, in the disks 18 and 22, of the insulation, are enlarged so that the trunnion can never come in contact with any part of the insulation. It will be observed also, that said central circular opening in the outer disk 23 is large enough to permit loose play therein of the 90 trunnion 4.

A continuous ringing bell 26 is connected by a lead 27 to a binding post 28, which is electrically connected to the disk 19, and a lead 29 extending from the bell is connected 100 through a battery 30, to the attaching portion 15, of the bracket.

In the operation of this form of my invention, the shade is pulled down and when lowered to the desired position, the pawls 105 forming a part of the well known roller shade construction should be out of engagement with the ratchet, and while the shade is under strain caused by the spring within the shade roller, a ring 31, connected to the 110 lower edge of the shade by means of a cord, is engaged upon a button 32, having a penetrating element 33, whereby the button may be secured to the wall at the required position to properly locate the shade. In this 115 position of the shade, the cylindrical trunnion 4, should be disposed within the openings in the plates 19 and 23, and resting upon the flattened portion 21, so that the trunnion remains out of contact with the 120 plate 23. This is accomplished by first drawing down the shade to the position desired or until the ring 31 is brought adjacent the button 32, or slightly below. Upon engaging said ring upon the button the trunnion 4, which previously had been moved 125 into contact with one end of the central opening in the disk 23, is now permitted to roll back upon the flat surface 21 of the disk 19, until a central position within the open- 130

ing is attained thereby placing the parts in readiness for actuation. In the event that an unauthorized person raises or lowers the shade, the trunnion 4 will be caused to roll 5 upon the flattened surface 21, until contact is made with the plate 23, whereupon electrical connection is established from the binding post 28, to the plate 19, through the trunnion to the plate 23, thence to the 10 bracket, through the circuit including the battery, and the bell, and back to the binding post. The bell thus continues to ring until a switch or the like (not shown) is moved to break the circuit. It will be observed that owing to the engagement of the 15 notch 14, upon the edge 13, longitudinal movement of the shade roller is absolutely precluded, thereby maintaining the trunnion in proper relation to the disk 23 for 20 engagement therewith.

For employing a contact closing shade supporting bracket of the form just described, in connection with a closed circuit system of wiring, attention is called to an 25 arrangement illustrated in Fig. 18, wherein 35 indicates a shade roller having a metallic cap 36 at each end which are connected by means of a conductor 37. One trunnion 38 is mounted in a contact making 30 bracket such as that just described, or one to be subsequently described, and adapted to close electrical communication between the metallic caps 36 and the body portion of the bracket through the trunnion 38. The 35 opposite trunnion of the shade roller may be supported in a bracket such as the form illustrated in Fig. 8 with continuous electrical contact therewith. A relay 39 is provided having electro-magnets 40 adapted to 40 attract an armature 41 having a resilient contact member 42, for engagement with an adjustable contact 43. The adjustable contact 43 and the movable armature 41 are electrically connected by means of conductors 44 and 45 respectively between which however, an audible signal 46 is interposed 45 in series. A source of current 47 is also interposed within one of the conductors 45. A second relay 48 is provided having electro-magnets indicated at 49 for attracting 50 a movable armature 50 having a spring contact member 51 adapted by movement of the armature 50 to oscillate between adjustable contact 52 and 53, the contact 53 being engageable 55 when the armature 50 is attracted by the electro-magnet, the contact 52 conversely being engaged when the armature 50 is released, the armature being retained in said released position by means of a light 60 spring 53 associated with a set screw 54 for varying the tension of the spring.

The magnets 40 and 49 are all connected in series, the free conductor from the magnet 49 being led to the shade roller bracket 65 for supporting the trunnions 38. A conduc-

tor 56 extends from the said brackets, to the terminal of a resistance coil 57, the opposite terminal of said coil indicated at 58 being electrically connected to the opposite roller supporting bracket. Said roller supporting 70 bracket is then connected by means of a lead 59 to one terminal of a source of current 60, the other terminal of said source of current, being connected by means of a lead 61 to the free terminal of the magnet 40. 75

In the operation of this closed circuit system, current is permitted to flow continuously through both set of magnets 40 and 49, owing to the interposition of the resistance 80 57 in the circuit the current is only sufficient to energize the magnets 40, the current not being sufficient to energize the magnets 49, and as a consequence the armature 41 is held attracted by means of its magnet thereby disposing the contact member 42 thereof out 85 of engagement with the adjustable contact 43. The armature 50 of the magnet 49 is thus held against the adjustable contact 52 and the spring 51 thereof held out of contact, with the adjustable contact 53. In this 90 condition of the system, current flows we will say, from the source of current 60 to the leads 61 through the magnets 40 and 49, passing through the lead 55 to the right hand shade roller supporting bracket, from 95 said bracket to the conductor 56 through the resistance 57, thence through the conductor 58 to the left hand bracket, and from the same returning by means of the conductor 59 to the source of current 60. The resistance 57 is thus placed in series with the 100 said relay magnets.

When however, the shade roller is rotated by movement of the shade so as to make an electrical contact, current is permitted to 105 flow through the trunnion 38, through the conductor 55 and the magnets 49 and 40, through the conductor 61 to the source of current, from thence passing by means of the conductor 59 to the left hand shade roller 110 supporting bracket, from the same to the metallic cap 36, thence through the conductor 37 to the right hand metallic cap 36 to the trunnion 38. In this manner the resistance 57 is shunted or thrown out of the circuit, and as the result of this the current is sufficiently increased to energize the magnets 49 of the relay 48, enough to attract armature 50 thereby bringing the spring contact 51 and the adjustable contact 53 into engagement. It will be noted that the contact 53 is connected by means of a lead 62 to the conductor 44 of the local bell circuit, the armature 50 being connected by means of a similar conductor 63 to the conductor 45 at 115 a point outside the source of current 47. Consequently, current is permitted to flow from said source of current 47 through the conductor 63, the armature 50, and contact 51, to contact 53, thence returning to the 120 125 130

conductor 62 to the bell and back to the battery 47. The bell is then continuously rung until disconnection of the circuit is established.

5 An important feature of the foregoing system lies in the fact that it immediately betrays the fact should the instrument or wiring be tampered with or get out of order, for instance, should any conductor in the 10 main circuit be broken the magnet 40 of the relay 39 will become obviously deenergized, thereby releasing the armature 41 thereof which drops and makes contact with the adjustable contact 43. As a result of this contact, current from the battery 47 is permitted to flow through the conductor 45, through the armature 41 and spring contact 42 to the contact 43, from thence through the conductor 44 to the audible signal 46 and back 15 to the battery. The signal is then sounded, and continues to ring until the broken place is discovered and connection reestablished, or the local circuit broken.

20 As a modified form of roller supporting 25 bracket, for use in connection with open or closed circuit wiring systems, I have illustrated in Figs. 14 and 15, a pair of such brackets, the bracket of Fig. 14 being adapted to support the left hand trunnion of the 30 shade roller, and comprises a body member 64 having a rectangular central opening 65 to receive the trunnion and embodying means for preventing longitudinal movement of the roller in the manner carried out 35 in the brackets shown in Figs. 8 and 9. The view of the bracket illustrated in Fig. 14 is substantially a rear face view of the form shown in Fig. 13.

40 In Fig. 15, the right hand bracket is set forth and comprises a body portion 64 having an attaching portion 67 whereby the same may be secured to the front face of the window casing, the body portion 64 being rounded, and provided with a central opening 45 68. A disk 69 is secured by suitable fastenings which may pass through openings 70 to the body portion 64, said disk 69 being of insulation and provided with an extension opening 71 substantially circular for 50 the major portion of its circumference but is provided at its lower side with a flattened portion 72 which is inclined along a line extending outwardly from the bracket and downward. The openings 68 and 71 are 55 thus disposed out of alinement, and in addition thereto the opening 71 as aforesaid is provided with a lower inclined flattened head. Therefore, when the rounded terminal is disposed within the opening 71, its 60 natural position would be toward one end of the flattened portion 72, namely its lower end, thereby centralizing the trunnion within the opening 68.

65 In the operation of this form of bracket, when the shade is lowered, the trunnion 72

is rolled up the incline and remains in contact with the edge of the opening 68 as long as the shade is being moved downward. When the shade is lowered to its desired distance, it is slightly released, or permitted to move up until the pawls engage their ratchets to retain the shade roller in moved position, and this slight backward movement permits the trunnion 72, to move down the incline again until it becomes centralized 75 within the opening 68 consequently out of contact with its edges. Obviously, in this position any attempt to raise the shade would first necessitate a slight downward movement, and this movement would be sufficient 80 to again roll the trunnion 72 up the incline until it engages with the edge of the opening 68, whereupon an electrical contact is made between said trunnion and the body portion 64 and if these parts are placed in 85 circuit with a signaling arrangement, an actuation thereof will readily follow.

90 In the foregoing described form of contact making brackets, it will be noted that in each instance the circuit through the bracket is normally open, contact being made upon engagement with the trunnion of the shade roller with some other part. This is true even in the case of the arrangement illustrated in Fig. 13 wherein the circuit 95 is normally closed. I have however, illustrated in Figs. 16 to 19, views in whole and part of a form of shade roller supporting bracket which is designed to permit a continual flow of current therethrough, the actuation of the signaling mechanism being initiated when the continuous flow of current as above set forth is stopped. With 100 this in view, the bracket comprises a base plate 73 flanked at either side with integrally formed ears 74 provided with means whereby the same may be fastened to the inner facing of a window frame. The said member is provided with a central opening 75, and a disk of insulating material 76 is secured to the face of the member 73, by means of suitable threaded or other fastenings 77. The disk 76 is provided with a central opening 78, which is provided with a lower horizontal flattened portion 79, having at an intermediate point therein a notch 80. The disk 76 is so placed that its central opening is in registration with the opening 75 of the member 73, and a metallic disk 81 is placed in contact with the disk 76, and held thereto by means of the threaded fastenings 77 which penetrate openings in both of the disks 76 and 81. The disk 81 is provided with a central opening 82 quite similar in form to the opening 78 of the disk 76, and also having a lower flattened horizontal portion 83. These disks are arranged with their openings in alinement, as illustrated in Fig. 17. It will however be noted in connection with the disk 81, that it is provided with a 130

radially extending and normally vertical lug 84 which extends into the central opening 82, and said lug is adapted, when the disks 76 and 81 are in engagement, to exactly 5 cover the notch 80 of the insulating disk. In this manner the top face of the lug 84 exactly coincides with the level of the horizontal portion 79 of the disk 76 and the disks and face portion when assembled present an appearance quite similar to that 10 illustrated in Fig. 16.

In the operation of this form of bracket, the trunnion of the shade roller is normally 15 designed to rest centrally of the opening in the disk, and to rest upon the lug 84 of the disk 81, thereby establishing electrical communication between the trunnions and the base portion 73 of the bracket, and if these parts are in circuit with a relay and a source 20 of current, the relay will be continuously energized. The trunnion is disposed in its central position in a manner similar to that employed in connection with the other forms, viz: by moving down the shade to the 25 desired position, whereupon the trunnion will roll upon the horizontal portion of insulating disk, until the shade is lowered to the desired distance. Upon slightly releasing the shade, in order to permit the pawls 30 of the roller to engage their ratchets or to dispose the ring of the shade upon a button as described in connection with the first form, the shade is permitted to be raised slightly under the tension of its spring 35 whereupon the trunnion rolls back again to a central position. Contact is thus continuously made and current flows through the bracket and trunnion until the shade is tampered with, whereupon the trunnion rolls, to 40 either one side or the other as the case may be, the horizontal portion of the insulating disk, whereupon contact is broken and the relay actuated, resulting in a closing of a local circuit and the sounding of the alarm. 45

In connection with this form of bracket, a bracket for supporting the opposite end of the shade roller is illustrated in Fig. 23, from which it will be noted that it comprises a base portion 85 flanked by integrally 50 formed ears 86 whereby the same may be fastened to the side casing of a window, said body portion having a rectangular central opening 87, intersected by a radial passage 88, which extends from the edge of the body 55 portion and intersects the central rectangular opening. A disk of metal 89 is provided with rectangular openings similar to the opening in the body portion and a radial opening, said disk being placed against the body portion 85 with the openings in registration. A metallic disk 90 is next disposed in engagement with the disk 89, said disk 60 90 having a rectangular opening which however, is shorter in length than the opening 65 in either the disk 89 or the body portion 85,

whereupon an edge 91 is defined, the same being illustrated to advantage in Fig. 23. Another disk of metal 92, is applied to the metallic disk 90, said disk having a central opening and radial openings corresponding 70 to the openings in the disk 89 and the body portion 85, and the whole is secured together by means of threaded or the like fastenings 93, which penetrate the body portion of all 75 of the disks.

In connection with this form of bracket, the trunnion must be provided with a notch like and for the same purpose as 14 in Fig. 12 and the trunnion is passed through the rectangular opening in the bracket, and the notch seated over the edge 91; whereupon longitudinal movement of the shade roller is precluded.

As a further modification of the principle employed in connection with the form of contact breaking shade roller supporting bracket, I have provided a form illustrated in Figs. 20 to 22. It will be noted that it comprises a substantially circular body portion 94, flanked at either side with integrally formed ears 95 whereby the same may be fastened to the side casing of a window, the said body portion being provided with a central round opening 96. A disk of insulating material 97 is next placed against 90 the member 94, said disk 97 having a central opening adapted for registration with the opening 96, but in addition thereto having a lug projecting within the central opening 98 of the disk, said lug being indicated at 99 and which provides an upper surface 100 which is inclined slightly from the horizontal, and extends from the edge of the opening in a downward direction, and a vertical portion 101, which is disposed to the left 105 hand side of the vertical diametrical center of the disk. A second disk 102, is provided however, formed of metal, and having a circular opening 103 disposed eccentrically and preferably to the left hand side of the 110 disk as indicated in Fig. 22. Into opening 103 extends a lug 104 which is integral with the disk 202 and has an upper surface 105 which is inclined to the same extent and direction as the inclined portion 100 of the disk 97, and when the disks are placed in close relation the one inclined portion forms a continuation of the other. The lug 104 is also formed with a vertical portion 106 which is adapted to coincide with the vertical portion 101 of the disk 97. The disks are assembled and are secured to the member 94 by means of suitable threaded or the like fastenings 107, and the appearance of the device when assembled is substantially 115 that indicated in Fig. 20, from which it will be noted that a trunnion is disposed therein, owing to the inclination of the flat surfaces 100 and 105, the trunnion will have a tendency to rest at the lower portion thereof and 120 125 130

consequently normally in contact with the plate 102. In this manner if the trunnion and plate 102 or body member 94 which both are in electrical contact, are placed in series with a relay and a source of current, the relay will be continually energized. When the trunnion is dislodged from its seat by slightly lowering the shade in preparation to raising the same, the contact between the trunnion and plate 102 will be broken, thereupon actuating the sounding mechanism in the manner before described. The brackets and shade rollers of an entire dwelling may be suitably arranged in a circuit so that a movement of the shade of one shade roller will result in actuation of the signal.

While I have illustrated and described my invention with some degree of particularity, I realize that in practice various alterations thereover may be made, and I therefore reserve the right and privilege of changing the form of the details of construction, or otherwise altering the arrangement of the correlated parts without departing from the spirit of the invention or the scope of the appended claims.

Having thus described my invention what I claim as new and desire to secure by Letters Patent is:—

1. A curtain shade alarm device including a shade provided with a trunnion, a contact, and a second contact on which said trunnion may roll to engage the first mentioned contact.

2. A curtain shade alarm device including in combination a shade roller having a trunnion, a bracket to receive the trunnion, contacts insulated from each other mounted upon the bracket and having alined open-

ings enlarged relatively to the trunnion to receive the latter, one of said contacts normally supporting the trunnion out of engagement with the other contact.

3. A curtain shade alarm device including in combination a shade roller having a conductor portion, supporting brackets therefor, one of said brackets permitting lateral movement of one end of the shade roller and having contact means engageable by the conductor portion upon such movement.

4. A curtain shade alarm device including in combination a shade roller having a trunnion at each end, supporting brackets therefor, one trunnion of the shade roller having a notch, a projection on its supporting bracket engaging the notch to prevent longitudinal movement of the shade roller, and a circuit closer in the path of the remaining trunnion of the shade roller and closable by movement of the said trunnion.

5. A curtain shade alarm device including in combination a shade roller having a conductor portion, supporting brackets therefor, one of said brackets permitting lateral movement of the shade roller and having contact means engageable by the conductor portion, alarm circuit means closable by the engagement of said portion with the contacts, a depending lug on the other trunnion, and means on the other bracket to engage the lug to prevent longitudinal movement of the shade roller.

In testimony whereof I affix my signature in presence of two witnesses.

JOHN HAVRAN.
